CIRCUIT CONTROLLING DEVICE

Edward L. Barrett, La Grange, Ill., assignor to
 Utah Radio Products Company, Chicago, Ill., a
 corporation of Illinois

Application November 14, 1936, Serial No. 110,875

12 Claims. (Cl. 200—87)

The invention relates to electric circuit controlling devices and more particularly to such devices commonly designated as electromagnetic relays.

5 A general object of the invention is to provide a new and improved device of this type which is not only especially compact and small in its over-all dimensions but also made up of only a few component parts, each of which may be manufactured very cheaply in large quantities, these advantages being had, however, without any sacrifice in sensitivity or effectiveness of operation of the finished device.

Another object of the invention is to provide 15 such a device in which a major portion of the component parts may be formed from sheet metal by simple stamping operations.

A further object of the invention is to provide 20 a device of the type described which permits of sufficiently large tolerances in the outline dimensions of its component parts so that they may be fashioned by stamping operations without subsequent machining and without adversely affecting the sensitivity of the completed device, 25 and in which uniform operating characteristics may be had for a large number of devices made by quantity production methods.

Further objects and advantages of the invention 30 will become apparent as the following description proceeds and the features of novelty which characterize the invention are pointed out with particularity in the claims annexed to and forming a part of the specification.

For a better understanding of the invention, 35 reference may be had to the accompanying drawing in which,

Figure 1 is a perspective view of a relay unit 40 embodying the invention, the enclosing casing and mounting for the relay being indicated in dot-dash lines.

Fig. 2 is an enlarged side elevation of the relay shown in Fig. 1.

Fig. 3 is an exploded perspective view of the 45 relay shown in Figs. 1 and 2.

For purposes of illustration, the invention has 50 been shown as embodied in a small compact relay adapted for use in electric control circuits of various sorts. The relay illustrated includes as its principal elements a frame designated generally by the numeral 10 carrying an electromagnetic energizing winding 11 and a movable armature 12. The armature serves to effect relative movement between a pair of cooperating contacts 13 and 14 in response to energization of the 55 actuating winding 11.

The frame is preferably a one piece structure which includes a part forming a magnetizable core for the actuating winding 11, as well as a part forming a support for the armature 12. In the preferred construction illustrated, the frame 5 10 is generally F-shaped in form, thus including a C-shaped portion for the relay proper and an upright supporting leg 15. The C-shaped portion of the frame is made up of a central or upright leg 16 having laterally extending legs 17 10 and 18 projecting in spaced relation from its opposite ends. Such a frame may be readily formed by stamping the same from light metal stock having a relatively high magnetic permeability. 15 Soft sheet iron having a high magnetic permeability and low retentivity, is suitable for this purpose. The generally flat contour of the frame 10 adds materially to its simplicity of manufacture.

The electromagnetic energizing winding 11 is 20 preferably wound in place rather than being pre-formed. In the construction illustrated, a pair of coil retaining end members 19 and 20 fashioned by stamping from insulating sheet material are disposed in spaced relation on the central leg 16 of the frame 10. Suitable centrally located apertures 21 and 22 are formed in the coil end members 19 and 20, respectively, these apertures being of sufficient size that the end members may be slipped over the frame leg 17 25 and onto the central frame leg 16. When in position on the central leg 16, the end member 20 abuts against the lateral leg 18 and a shoulder 23 formed in the frame while the opposite end member 19 abuts against the second laterally 30 extending leg 17.

An improved and simplified contact supporting arrangement is preferably utilized to prevent skewing of the coil and member 19. This arrangement includes a flat stamped piece of 40 insulating material 24, such as fabric reinforced Bakelite, which may be secured to the frame 10 in face-to-face relation therewith by rivets 25 passing through aligned apertures 26 and 27 in the piece of insulating material and frame. In 45 assembling the relay illustrated, the coil end members 19 and 20 are first slipped on the frame and then the piece of insulating material 24 is riveted in place. The member 24 projects laterally from the frame forming in effect a shoulder corresponding to the shoulder 23. The coil end members may be held in spaced relation by a piece of kraft paper wound around the frame leg 16 between them. The coil 11 is then formed 50 by winding fine insulated wire about the frame 55 by

between the coil end members. In performing this winding operation, the projecting end 15 of the frame 10 may be readily secured in the chuck of an automatic winding machine.

5 The elongated rigid armature 12 preferably has a free floating pivotal mounting so that the relay will have a high degree of sensitivity. In general, the armature 12 is disposed substantially in the plane of the frame 10 and extends between the laterally projecting arms 17 and 18. In order to simplify its construction, the armature 12 may also be fashioned as a stamping from light gauge sheet metal stock having a high magnetic permeability and low retentivity such as soft iron. Upon reference to Fig. 3, it will be seen that the armature illustrated is generally flat in shape and has an enlarged lower end 28 provided with outwardly extending ears 29. The ears or projections 29 are interfitted with 20 complementally formed projections on the frame to provide a loose pivotal mounting. To this end, an L-shaped stamped sheet metal member 30 is secured to the frame arm 18 by a rivet 31 passing through registering apertures 32 and 25 33. A corresponding enlarged aperture 34 is formed in the armature 12 so that the head of the rivet will not interfere with the movement of the armature. Laterally extending ears or projections 35 on the member 30 overlie the ears 29 30 on the armature 12, thus preventing upward movement thereof. The opposite or free end of the armature 12 overlies the frame arm 17. Consequently, when the winding 11 is energized, the frame arm 17 will be magnetized and attract 35 the adjacent end of the armature.

Resilient means is provided for yieldably biasing the armature 12 against movement toward the magnetizable frame arm 17. Thus, an elongated helical tension spring 36 extends between 40 the armature and the frame. One end of the spring is secured to the armature by a hook 37 struck up from the side thereof and the opposite end of the spring is secured to an ear 38 on the L-shaped member 30. The hook 37 projects a 45 substantial distance above the armature so that the spring tension will be applied with a good leverage. It has been found that much more uniform operation will be had for relays of the type described produced in large quantities when 50 a spring is used having a comparatively large number of turns. The spring 36 illustrated has approximately forty turns. When a spring having turns of this general order of magnitude is used, the over-all strength of the spring will be 55 about the same even though the strength of one or two of the individual turns may vary somewhat due to slight inaccuracies in the manufacturing operations performed thereon. Also when the spring is stretched during operation the distortion of each individual turn is minimized because of the distribution of the stretching throughout a large number of turns. Upon reference to Fig. 2, it will be seen that the spring 36 is arranged at an acute angle with respect to 60 the armature 12. The elongation of the armature 12 makes it possible to utilize a long spring without the necessity of providing a separate securing member for its outer end.

A fixed stop limits the oscillatory path of 70 movement of the armature 12. This stop is preferably disposed out of contact with the armature except at the outer extremity of its path of movement so that the sensitivity of the relay will not be affected by friction between the stop and 75 the armature. In the construction illustrated, a

headed non-magnetic screw 39 constitutes a convenient method of providing such a stop. This screw is threaded in a tapped hole 40 formed in the frame arm 17 and passes through an aperture 41 in the armature 12. An eyelet 41a made of brass or other non-magnetic material is inserted in the hole 41. The inner flange on the eyelet prevents direct contact between the armature and frame so that the armature will not be retained in closed position by residual magnetism. The inside diameter of the eyelet 41a is substantially larger than that of the shank of the screw 39. In assembling the relay at the point of manufacture, the screw 39 is adjusted until the spacing between the contacts 13 and 14 15 is set at a desired amount. The screw 39 may be rigidly fixed in this position by a drop of solder 42 (Fig. 2) on its inner end.

As was previously noted, a very simple contact supporting structure is herein contemplated. 20 The contact insulator 24 may be readily formed by stamping, or some similar operation, from a sheet of insulating material and the use of the usual screw-machine made insulating parts is obviated. The contacts 13 and 14 are preferably 25 made of silver and are generally cylindrical in shape. The relatively fixed contact 14 is secured to the outer end of an electrically conductive metal spring finger 43 made of phosphor bronze or the like. This spring finger is fastened 30 to the piece of insulation 24 by suitable rivets passing through registering holes 44 and 45 while the projecting outer end 46 of the spring finger constitutes a terminal lug. The movable contact 13 is secured to the outer end of the armature 12 and for this purpose, has a shank portion which is inserted in a registering hole 47 formed in the free end of the armature, the outer end 35 of the contact point shank being peened over the adjacent edges of the hole. The spring finger 40 24 is sufficiently distortable to permit adjustment of the contact spacing.

The relay described is preferably provided with a plug-type mounting in order to facilitate its insertion and removal in associated apparatus. 45 The mounting plug shown in Fig. 1 includes an insulating disk 48 having conductive metal prongs 49 projecting from its lower side and adapted to be received in a complementary plug receptacle. A laterally extending ear 50 projects 50 from the lower end 15 of the relay frame 10 and one of the prongs 49 projects through an aperture 51 therein. The relay is thus rigidly secured in position on the plug insulating disk 48. A cylindrical cup-shaped casing 52 surrounds the 55 relay when thus mounted.

In case the relay is to be used in the proximity of radio apparatus, the casing may be made of metal in order to shield the radio apparatus from radio frequency oscillation set up by the action of 60 the contacts 13 and 14.

In the operation of the device described above, current is supplied at will from a control circuit to the actuating winding 11 through conductors 53 and 54 which are respectively connected to 65 two of the plug prongs 49. One terminal of the circuit to be controlled is connected to the fixed contact 14 through one of the plug prongs 49, conductor 55, and mounting finger 43. The other terminal of the controlled circuit is connected to 70 the movable contact 13 through one of the plug prongs 49 which is secured to the relay frame, a pig-tail connection 56 and armature 12. When the actuating winding 11 is energized, a magnetic field is set up thereby in the frame 10, thus at- 75

tracting the armature 12 and causing the contacts 13 and 14 to be closed. As soon as the actuating winding 11 is deenergized, the armature is again moved to its open position by the 5 biasing spring 36.

From the foregoing, it will be apparent that a circuit controlling device has been provided which is extremely compact and small in its overall dimensions and which can be cheaply manufactured. The minimization of the cost of manufacture is, in a large part, due to the fact that a major number of the component parts can be formed by simple stamping operation and in addition, the design is such that fine machining and 10 careful adjustment of parts is not required. Although a particular preferred embodiment of the invention has been shown and described in some detail for purposes of illustration, there is no intention to thereby limit the invention to such 15 embodiment but, on the other hand, the appended claims are intended to cover all modifications within the spirit and scope of the invention.

I claim:

1. An electromagnetic relay comprising, in combination, a flat frame fashioned from a single piece of sheet metal and having a generally C-shaped portion including a central leg with laterally extending legs projecting from opposite ends thereof, an electromagnetic energizing 25 winding disposed about said central leg, a pair of cooperating relatively movable contacts, means including an elongated rigid armature member disposed substantially in the plane of said frame for effecting relative movement of said contacts 30 in response to energization of said winding, and means for pivotally supporting one end of said armature on one of said laterally extending legs and with the other end thereof overlying the second laterally extending frame leg.

2. An electromagnetic relay comprising, in combination, a flat frame fashioned from a single piece of sheet metal and having a generally C-shaped portion including a central leg with laterally extending legs projecting from opposite 35 ends thereof, an electromagnetic energizing winding disposed about said central leg, a flat piece of insulating material secured to said frame in face-to-face relation therewith and projecting therefrom, a contact carried by the projecting portion of said piece of insulating material, a second contact cooperating with said first-named contact, an electromagnetic energizing winding disposed about said central frame leg, means including an elongated rigid armature member 40 disposed substantially in the plane of said frame for effecting relative movement of said second contact in response to energization of said winding, and means for pivotally supporting one end of said armature on one of said laterally extending legs and with the other end thereof overlying the second laterally extending frame leg.

3. An electromagnetic relay comprising, in combination, a flat frame fashioned from a single piece of sheet metal and having a generally C-shaped portion including a central leg with laterally extending legs projecting from opposite ends thereof, a pair of coil retaining end members disposed in spaced relation on said central frame leg and in abutment with the adjacent laterally extending legs, an energizing coil wound about said center leg between said coil end members, a pair of cooperating relatively movable contacts, means including an elongated rigid armature member disposed substantially in the 50 plane of said frame for effecting relative move-

ment of said contacts in response to energization of said winding, and means for pivotally supporting one end of said armature on one of said laterally extending legs and with the other end thereof overlying the second laterally extending 5 frame leg.

4. An electromagnetic relay comprising, in combination, a flat frame fashioned from a single piece of sheet metal and having a generally C-shaped portion including a central leg with laterally extending legs projecting from opposite ends thereof, a flat sheet material coil retaining end member having an aperture therein adapting the same to be slipped over one of said laterally extending frame legs and positioned on said central leg in abutment with the adjacent laterally extending leg, a flat piece of insulating material secured to said frame in face-to-face relation therewith and in abutment with said coil end member to prevent skewing thereof, a contact 10 carried by a projecting portion of said piece of insulating material, a second contact cooperating with said first-named contact, an energizing coil wound about said central frame leg in abutment with said coil end member, means including an 15 elongated rigid armature member disposed substantially in the plane of said frame for effecting relative movement between said contacts in response to energization of said winding, and means for pivotally supporting one end of said armature 20 on one of said laterally extending legs and with the other end thereof overlying the second laterally projecting frame leg.

5. An electromagnetic relay comprising, in combination, a flat frame fashioned from a single piece of sheet metal and having a magnetic core portion with laterally extending legs projecting from opposite ends thereof, a shoulder formed on said frame in alignment with one of said legs and on the opposite side of said core portion 25 therefrom, a pair of flat sheet material coil retaining end members having apertures therein adapting the same to be slipped over the other of said legs and disposed in spaced relation on said frame core portion, one of said end members being positioned in abutment with said shoulder and said one laterally extending leg, the other of said end members being positioned in abutment with said other leg, a flat piece of 30 insulating material secured to said frame in face-to-face relation therewith and in abutment with said last-named coil end member to prevent skewing thereof, a contact carried by a projecting portion of said piece of insulating material, a second contact cooperating with said first-named contact, an energizing coil wound about 35 said frame core portion between said coil end members, and means including an armature member mounted on said frame for effecting relative movement between said contacts in response 40 to energization of said winding.

6. An electromagnetic relay comprising, in combination, a flat frame fashioned from a single piece of sheet metal and having a generally C-shaped portion including a central leg with laterally extending legs projecting from opposite ends thereof, an electromagnetic energizing winding disposed about said central leg, a pair of cooperating relatively movable contacts, means including an elongated rigid sheet metal 45 armature member disposed substantially in the plane of said frame for effecting relative movement between said contacts in response to energization of said winding, and means including interfitting projections on one end of said armature 50 member.

ture and on one of said laterally extending frame legs for supporting said armature for free floating pivotal movement toward and away from the plane of said frame and with the free end of said 5 armature member overlying the second laterally extending frame leg.

7. An electromagnetic relay comprising, in combination, a flat frame fashioned from a single piece of sheet metal and having a generally C-shaped portion including a central leg with laterally extending legs projecting from opposite ends thereof, an electromagnetic energizing winding disposed about said central leg, a pair of cooperating relatively movable contacts, means 10 including an elongated rigid sheet metal armature member disposed substantially in the plane of said frame for effecting relative movement between said contacts in response to energization of said winding, and means including interfitting projections on one end of said armature and on one of said laterally extending frame legs for supporting said armature for free floating 15 pivotal movement toward and away from the plane of said frame and with the free end of 20 said armature member overlying the second laterally extending frame leg, said armature having an aperture therein, and a headed screw threaded in said frame and positioned in said aperture with the shank thereof out of contact 25 with the edges of said aperture for limiting the amplitude of movement of said armature by contact thereof against the head of said screw.

8. An electromagnetic relay comprising, in combination, a flat frame fashioned as a stamping 30 from a single portion of sheet metal having a relatively high magnetic permeability and low retentivity, said frame having a substantially rectangular coil portion and a laterally extending leg projecting from one end of said core portion, an energizing winding disposed about said 35 frame core portion, a pair of cooperating relatively movable contacts, means including a movably mounted flat rigid sheet metal armature member disposed substantially in the plane of 40 said frame and cooperating with said frame core portion and leg for establishing a closed low reluctance flux path linking said winding, and means including said armature for effecting relative movement between said contacts in response 45 to energization of said winding.

9. An electromagnetic relay comprising, in combination, a flat frame fashioned as a stamping 50 from a single portion of sheet metal having a relatively high magnetic permeability and low retentivity, an electromagnetic energizing winding disposed about a portion of said frame, a pair of cooperating relatively movable contacts, means including a flat rigid sheet metal arma- 55

ture member disposed substantially in the plane of said frame for effecting relative movement between said contacts in response to energization of said winding, and means for pivotally supporting said armature on said frame for movement toward and away from the plane of said frame. 5

10. An electromagnetic relay comprising, in combination, a flat frame fashioned as a stamping from a single portion of sheet metal having a relatively high magnetic permeability and low 10 retentivity and including two angularly disposed members lying in the same plane, an energizing winding disposed about a portion of said flat frame for setting up an electromagnetic field therein, a pair of cooperating relatively movable 15 contacts, means including a movably mounted flat rigid sheet metal armature member disposed substantially in the plane of said frame and cooperating with said angularly disposed frame members for establishing a substantially closed 20 low reluctance flux path linking said winding, and means including said armature for effecting relative movement between said contacts in response to energization of said winding.

11. An electromagnetic relay comprising, in combination, a flat frame fashioned as a stamping from a single piece of sheet metal in a generally F-shaped form, an electromagnetic energizing winding disposed about the upright portion of said frame between the laterally extending arms thereon, a pair of cooperating relatively movable contacts, means including an elongated rigid armature member disposed substantially in the plane of said frame for effecting relative movement of said contacts in response to energization of said winding, and means for securing the lower end of the upright portion of said frame to a suitable mounting member. 30

12. An electromagnetic relay comprising, in combination, a flat frame fashioned as a stamping 40 from a single piece of sheet metal in a generally F-shaped form, an electromagnetic energizing winding disposed about the upright portion of said frame between the laterally extending arms thereon, a pair of cooperating relatively movable contacts, means including an elongated rigid armature member disposed substantially in the plane of said frame for effecting relative movement of said contacts in response to energization of said winding, a mounting plug including an insulating member having electrically 45 conductive prongs projecting therefrom adapted to be detachably received in a complementary plug receptacle, a projection formed on the lower end of said upright frame portion, and means for rigidly securing said projection to said mounting plug. 50
